UNITED STATES PATENT OFFICE.

JAMES CASSIDY, OF CHICAGO, ILLINOIS.

TRACK-SANDING DEVICE.

1,301,103.

Specification of Letters Patent. Patented Apr. 22, 1919.

Application filed June 8, 1918. Serial No. 239,005.

To all whom it may concern:

Be it known that I, JAMES CASSIDY, a citizen of the United States, and a resident of Chicago, in the county of Cook and State 5 of Illinois, have invented certain new and useful Improvements in Track-Sanding Devices, of which the following is a specification.

This invention relates to a sanding device 10 which is installed on motor and other cars, for the purpose of sanding the track on which said cars are propelled.

The principal objects of this invention are to obtain a track sanding device operable at 15 either end of a car, by means of which, in a car having two trucks, sand may be discharged in front of the front wheels of each truck or back of the rear wheels in each truck, as is desired by the operator, and (by 20 modified construction of a movable valve member) to obtain a device by which sand may be discharged in front of the forward wheels in said trucks and also in front of said forward wheels and at the same time 25 in back of the rear wheels of said trucks.

Further objects of the invention are to obtain a device operable as above recited by means of which the operator will be advised as to which of the above recited results are 30 being effected by him through his manipulation of the handle controlling the device.

Further objects are to obtain a device which is not liable to get out of order, or be broken; which is economically made, and 35 is simple in construction.

To those familiar with the operation of electric motor cars provided with two trucks it is known that at times it is desirable to discharge sand in front of the forward pair 40 of the wheels on both trucks and at other times is desirable, to prevent the car from slipping down a grade, or to move with certainty in backing down said grade, to discharge sand to the back of the rear pair of 45 wheels of both trucks.

I have illustrated a device embodying this invention in the drawing accompanying and forming a part of this specification, in which,

50 Figure 1, is a diagrammatic view representing a side elevation of the body, platform, and wheels of a car; showing a device embodying this invention in elevation installed thereon.

55 Fig. 2, is a top plan view of said device. Fig. 3, is a horizontal section of a valve

forming a member of the device, taken on line 3—3 of Fig. 1, and viewed in the direction indicated by the arrows.

Fig. 4, is a top plan view of a handle 60 forming an element of the device, with a portion thereof broken away to show a horizontal section.

Fig. 5 is a horizontal section of a vertical shaft, with elements thereon which form a 65 part of the device, taken on line 5—5 of Fig. 1, and viewed in the direction indicated by the arrows.

Fig. 6 is an elevation of a modified construction of the operating handle of the 70 device.

A reference character applied to designate a given part indicates said part throughout the several figures of the drawing, wherever the same appears. 75

X, represents the body of the car. Y, Y' represent the platforms of body X.

Z represents sand boxes. Z' represent the wheels of a car. A, A' represent vertical shafts which are rotatably mounted on platforms Y, Y', respectively. B are handles which are removably mounted on the upper end of shafts A, A. B' is a strap at the upper end of shaft A. The strap B' is provided with a recess b, in the construction 80 of which is illustrated in Figs. 1 and 4; and with a projection b' having inclined face b'' in the construction illustrated in Fig. 6. In the construction which is illustrated in Figs. 1 and 4 C represents a tube (see Fig. 4), in recess b''' of handle B. D, represents a ball which is contained in tube C. The end d of the tube C is turned over onto the ball D so that said ball cannot be forced out of 85 said tube, and E represents a spring which is arranged to yieldingly hold the ball D against the turned end d of said tube. 90

The ball D registers with recess b and is forced thereinto by the spring E, when the handle B is turned into position with the valve F fully open. Valve F controls the admission of sand from the several sand boxes Z into the discharge pipes G. 95

In the construction of the several members which are mounted on handle B, as 100 illustrated in Fig. 6, the member D', pivoted on pin d', is substituted for ball D, and spring E' for spring E.

The construction of valve F which I preferably employ is represented in Fig. 3, in 110 which f represents the shell or casing of the valve; F' a pivotally mounted valve

member turning on pivot f' and f^2 a spring which yieldingly holds said valve member in position to close the aperture g' . Valves F are attached between two parts of pipes G 5 so that when the valve member F' closes aperture g' said valve member obstructs the passage of sand from receptacle Z through said pipe to the discharge end thereof. g^2 are broken lines which indicate an additional 10 aperture similar to aperture g , which is, at times, made in the valve member F'. This valve member F' has, when apertures g , g^2 , are made therein, two operative positions; in one of which the aperture g registers 15 with aperture g' and in the other of which the aperture g^2 registers with said aperture g' . The registration of these apertures g , and g^2 with aperture g' is controlled by the levers of the J series and the angular movement 20 of the valve member F' is sufficient to successively bring said aperture g and aperture g^2 over said aperture g' .

When valve member F' is turned on pivot f' so that aperture g therein registers with 25 aperture g' in the lower face of the valve casing sand is delivered from receptacle Z, through the pipe G in front of the forward wheel of each truck of the car, the size of the stream thereof being determined by the 30 angular movement of the valve member F'.

When aperture g^2 is provided in member F' and said member is given its greatest possible angular movement, sand will be discharged in front of the forward wheels of 35 each truck and also in back of the rear wheels of each truck.

The manner in which this movement of lever J produces corresponding movement of 40 valve member F', as hereinbefore described, is hereinafter set forth.

To permit sand to be discharged through the casing f of the valve F the valve member F' is pivotally moved to bring the aperture g (or g''), to register with aperture g' .

45 The turning of the valve member F' is effected by means of links H, which are, respectively, engaged at one end with arm or lever I and at the other end with the respective levers J, J', J², J³.

50 K, K', K², K³ are rocking shafts secured to the under side of body X, by any suitable means. L, L', L², L³ are levers which are rigidly secured to corresponding shafts of the K series. The several levers J, J',

55 J², J³ are also rigidly secured to corresponding ones of the rocking shafts K, K', K², K³. Said shafts are rocked by means of the connections of the M series about to be described. N, N', are chain wheels on shaft

60 A rigidly attached thereto. N², N³ are chain wheels which are rigidly attached together and are loosely mounted on shaft A. N⁴ and N⁵ are chain wheels rigidly mounted on shaft A'. N⁶, N⁷, are chain wheels which 65 are rigidly connected together and loosely

mounted on shaft A'. n are abutments which are rigidly secured to, or are integral with, the chain wheels N' and N⁵; and n' are like abutments which are rigidly secured to or are integral with the chain wheels N² 70 and N⁶. M is a connection which extends from the wheel N to the lower end of lever K. M² represents a connection which extends from the wheel N² to the upper end 75 of lever L³; M³ a connection which extends from wheel N³ to the upper end of the lever L'; and M⁴ a connection which extends from wheel N⁴ to the lower end of lever L'; M⁵ a connection which extends from wheel N⁵ to the lower end of lever L³; M⁶ a connection which extends from wheel N⁶ to the upper end of lever L; M a connection which 80 extends from wheel N⁷ to the upper end of lever L².

Upon inspection of Fig. 5, it will be seen 85 that the abutments n may be moved in the direction of the arrow lettered N⁸, over the space n² before the turning of the shaft A and chain wheels N, N' (or N⁴ N⁵) will bring said abutments n into engagement 90 with the abutments n' of the wheel N² (or N⁶), and until said abutments are brought into engagement or contact, as suggested, the movement of the chain wheels N, N' (or N⁴ N⁵) will not produce movement of 95 chain wheels N², N³, (or N⁶ N⁷), but after said engagement is made continued movement of the shaft A (or A') and the wheels N, N' (or N⁴ N⁵) will move the wheels N² N³ (or N⁶ N⁷) along therewith. The ball 100 D, hereinbefore described, enters the recess B on strap B', as hereinbefore stated, when the forward movement of the abutment n as last above described, is sufficient to bring the forward faces thereof into contact with 105 the rear faces of the abutments n'. Notice is thereby given, by the ball D entering said recess b, that said contact had been made and that any further movement of the handle B will also move chain wheels N² N³ 110 (or N⁶ N⁷). Such further movement can be made as the ball is yieldingly held in the recess b; but when said movement is made, knowledge of the same is given by the said ball, as it is forced out of said recess. 115

In the construction having the members mounted on handle B which is illustrated in Fig. 6, the end of the member D' which is adjacent thereto abuts against the abutment b', when the hereinbefore described 120 forward movement of abutments n bring the forward faces thereof into contact with the rear faces of abutments n'. No further movement of handle B can then be made until the end of said member D' which is 125 over the handle B is depressed to raise the other end thereof up so it may pass over abutment b'. When it is desired to sand the track to the rear of the rear wheels of the trucks of the car, said member D' is de- 130

pressed and handle B is further moved to move chain wheels N^2 and N^3 (or N^6 and N^7).

By the said last above described construction a positive act (to wit, depressing one end of member D') is required before sand can be discharged on the track to the rear of the rear wheels of the trucks and hence when aperture g^2 in member F' is used I prefer this construction.

I claim:—

1. A sanding device comprising vertical shafts rotatably mounted on platforms, wheels rigidly mounted on said shafts adjacent to the lower ends thereof, and additional wheels loosely mounted on said shafts, means connecting the rigidly mounted wheels to the loosely mounted ones so that upon the turning of said rigidly mounted wheels a measured angular distance further turning thereof will also turn said loosely mounted wheels, in combination with valves and connections between said wheels and said valves.
2. A sanding device comprising vertical shafts rotatably mounted on platforms, a handle adapted to be attached to said shafts, and said shafts respectively provided with means to indicate a measured angular movement of said handle, wheels rigidly mounted on said shafts adjacent to the lower ends thereof, and additional wheels loosely mounted on said shafts, means connecting the rigidly mounted wheels to the loosely

mounted ones so that upon the turning of 35 said rigidly mounted wheels said measured angular distance further turning thereof will also turn said loosely mounted wheels, in combination with valves and connections between said wheels and said valves.

3. A sanding device comprising vertical shafts rotatably mounted on platforms, bearings for the upper ends of said shafts adapted to permit angular movement thereof, a handle adapted to be attached to said shafts 45 and said handle provided with a movable member and a spring interposed between said movable member and said handle to yieldingly hold said movable member in position to indicate a measured angular movement of said handle, wheels rigidly mounted on said shafts adjacent to the lower ends 50 thereof, and additional wheels loosely mounted on said shafts, abutments on the rigidly mounted wheels and abutments on the loosely mounted ones, said abutments positioned so that upon the turning of said handle said measured angular distance further turning thereof will bring said abutments into contact and turn said loosely 55 mounted wheels, in combination with valves and connections between said wheels and said valves.

JAMES CASSIDY.
